United States Patent Office.

JONATHAN MOORE AND WILLIAM WILKINSON, OF BROOKLYN, NEW YORK,
ASSIGNORS TO JONATHAN MOORE AND A. HORTON, OF SAME PLACE.

Design No. 4,808, dated April 11, 1871.

DESIGN FOR AN ORNAMENT FOR FOUNTAINS, &c..

The Schedule referred to in these Letters Patent and making part of the same.

We, JONATHAN MOORE and WILLIAM WILKINSON, of Brooklyn, in the county of Kings, State of New York, have invented and produced a new and original Design for Ornaments on Fountains and Vases, of which the following is a specification.

Our design we may distinguish, for convenience, by the term "leaf, shell, and frog." It is composed of oval leaves and shells arranged alternating, as represented, with frogs in relief in the angular recesses.

The nature of the design is fully represented in the accompanying illustrations, to which reference is made.

Figure 1 is an outline of the contours of the several members, and

Figure 2 is a photographic illustration, giving a fuller view of the complete work.

The work will ordinarily be made in cast-iron, painted, bronzed, or otherwise protected; but the design is equally applicable to work in other materials.

We claim as our invention—

The design herein shown, which we may denominate leaf, shell, and frog, for ornamentation of fountains and vases.

In testimony whereof we have hereunto set our names in presence of two witnesses.

JONATHAN MOORE.
WILLIAM WILKINSON.

Witnesses:

JAMES DENBIGH,
BENJAMIN MORRISON.
